DISHWASHING MACHINE

Edgar S. Stoddard, Berwyn, Ill., assignor to The Conover Company, Chicago, Ill., a corporation of Illinois

Application March 3, 1932, Serial No. 596,427

6 Claims. (Cl. 137—21)

The present invention relates to dishwashing machines in general, and has particular reference to improvements in spray-projecting dishwashing machines which are preferably of the detached or movable type.

One of the objects of the invention is to provide a simplified frame and tank structure giving an improved ease of assemblage and a sturdy structure.

10 Another object is to provide an improved drain valve for the dishwashing tank.

An improved inlet and outlet pipe arrangement adjustable vertically and horizontally for the ingress and egress of washing liquid is a further object of this invention.

15 An additional object is an improved cover ventilator and the elimination of cover clamps.

These and other objects will appear from the following description and from the accompanying drawings, in which

Fig. 1 is a partial cross-section of the assembled machine;

Fig. 2 is a cross-section of the cover ventilating member viewed along the line 2—2 of Fig. 1;

20 Fig. 3 is an enlarged cross-section of the operating and water actuating mechanism along line 3—3 of Fig. 1;

Fig. 4 is a partial elevation of the rotary drain valve actuating mechanism showing the overflow shield;

Fig. 5 is a vertical section of the cover hinge along line 5—5 of Fig. 6;

Fig. 6 is a sectional plan view of the cover hinge along line 6—6 of Fig. 5;

25 Fig. 7 is a sectional view through the combined inlet and outlet water conduits;

Fig. 8 is a sectional plan view along line 8—8 of Fig. 7;

Fig. 9 is a plan view of the silver rack;

40 Fig. 10 is a sectional view of the silver rack along line 10—10 of Fig. 9;

Fig. 11 is a perspective of the separated tank frame structure; and

45 Fig. 12 is a plan view of the interior of the tank bottom as shown in Fig. 1, showing the baffle structure on the impeller guard with the upper structure of the guard cut away.

The machine disclosed in the drawings is of the type utilizing a spray-projecting impeller for hurling washing water against dishes which are held in racks thereabove.

With reference to the drawings and more specifically to Figs. 1 and 11 thereof, it will be seen that a tank 18 is supported within a frame 10.

55 Frame 10 comprises a circular band 11 to which

are affixed by welding or other suitable means three depending legs 12. Each of these legs carries a rubber tired caster 13. As most dishwashing machine tanks are of vitreous enamel finish, the difficulties ordinarily encountered in attaching various operating elements of the machine to the tank wall are overcome and damage to the tank while the machine is in operation is avoided by mounting these operating elements on the frame structure.

10 Supported between the legs 12 of the frame is a brace or spider 17. This spider holds the legs firmly in place and prevents any buckling thereof when the machine is moved.

The tank 18 is cylindrical in shape and open at its upper end. The rim of the open end of the tank is curved outwardly and downwardly to form a lip or hooked flange 19. When the tank 18 is dropped into frame 10, the lip 19 engages band 11 and holds the tank suspended therefrom.

15 The structural formation of the tank 18 itself is similar to that disclosed in my copending application, Serial No. 389,696, filed Augst 31, 1929. As shown, it has an inwardly and downwardly sloping bottom 20 which becomes more inclined toward the central portion as at 21, terminating in a depressed portion which forms a well chamber 22 and a pump chamber 25 immediately thereunder. The bottom of the well chamber 22 slopes downwardly towards its center and is stepped at 23 to provide a seat for a pump chamber cover 24. The bottom of the pump chamber 25 is apertured at 26 to receive the impeller shaft mechanism which extends upwardly therethrough into the main portion of the tank 18.

20 The impeller operating mechanism is supported from the floor of the pump chamber 25 in such a manner that the tank 18, the spider 17 and the motor are all rigidly drawn together so as to reduce vibration to a minimum.

25 Referring particularly to Figs. 1 and 3, a motor 15 is rigidly affixed to an iron spinning 70 by bolts 71. The top of the spinning is provided with a recessed shelf portion which receives a lower noise insulator 74. Resting upon this lower insulator 74 is the spider or brace 17 and on top of the spider, and between it and the bottom of the pump chamber is a cork gasket 75 which helps to prevent the leakage of water from the pump chamber down into the motor 15.

30 Fixed to the inner side of the bottom of the pump chamber is the upper noise insulator 76 and a plate 78. This assemblage is rigidly held together by elongated bolts 77 which extend

55

downwardly through aligned apertures in the plate 78, insulator 76, the bottom of the pump chamber, gasket 75, spider 17, the spinning 70, and insulator 74 and are fastened within the 5 spinning by being screwed into plate 73.

Lower insulator 74 is preferably substantially thicker in its outer portions so that as the bolts 11 are tightened the outer portions of the insulator will be compressed until they are of the 10 same thickness as the center portion.

When tank 18 is dropped into the frame 10, the pump chamber bottom and the spider 17 are preferably spaced slightly apart. By tightening the bolts 11, the spider 17 is drawn up to 15 the tank bottom and the frame, tank, and motor are held rigidly together.

A bearing tube 72 is screwed into an upward annular extension of plate 73, and extends upwardly into the interior of tank 18 through the 20 aperture 26 in the pump chamber bottom.

An impeller shaft 79 is rotatably mounted within the bearing tube 72 and is connected to a motor shaft 81 by a coupler 82 which is enclosed within the spinning 70. To the upper end 25 of the impeller shaft 79 an impeller 83 is affixed by slot and key arrangement 84. A nut 85 is screwed on to the end of the shaft 79. Screwed to the impeller 83 is the pump tube 80 which extends downwardly into the pump chamber 25 30 and carries pump blades 86.

The impeller 83 is of the spray-projecting type and hurls water contained in tank 18 against dishes and silverware contained in racks 116 and 120, respectively, provided in tank 18.

As shown in Figs. 1, 3 and 4, the pump chamber cover 24 has a central aperture provided with an upwardly extending collar 100 which has a plurality of drain outlets 101 therein. A rotatable valve actuating ring 105 is seated upon 35 the top of the collar 100. The inner rotatable valve plug 102, provided with drain outlets 104, is mounted within the collar 100 by means of the regulating nut 106. This nut permits the vertical regulation of plug 102 so that its openings 40 104 may coact with outlets 101 of the collar 100. When proper adjustment is obtained, the nut 106 and the ring 105 may be soldered together 45 so that the adjustment of plug 102 will not vary during operation of the machine.

The ring 105 has an actuating arm 107 carrying a post 108 which receives and holds one end of a drain valve control wire 109. The drain control wire 109 is slidably enclosed within a 50 drain wire tube or housing 110 which leaves the well chamber 22 at a point beneath the apron 90. The housing 110 follows the general contour of the tank wall 18 to the switch box 14 on the frame band 11. The upper end of control wire 109 is attached to the drain handle 16.

Rigidly affixed to the switch box 14 is a drain handle tube 5 having a projecting pin 6 extending therefrom. The housing 110 is affixed to the lower end of this tube 5. The drain handle 16 extends through tube 5 and is slotted to receive pin 6 to prevent rotation of the handle 16. By preventing the twisting of handle 16 breakage 65 of the drain wire is avoided.

The housing 110 is rigidly affixed to the well chamber 22 wall at its lower end by a water-tight bushing 111 which is threaded upon its well chamber interior portion. Over this threaded portion is screwed an annular nut 112 and suitable washers are supplied to make the joint 70 water-proof. A hole is bored through this bush-

ing preferably at the angle of the housing 110. The housing is passed through this hole and soldered or welded into place. By this method the entire drain valve wire and housing may be removed without injury to the tank wall. 5 Leakage is prevented by elimination at this point of packing glands and moving parts. When the drain handle 16 is in the lowered position shown in Fig. 1, the drain valve is closed. By raising the drain valve handle 16 the drain valve plug 10 102 is rotated so that its openings 104 are in alignment with openings 101 of collar 100, thereby permitting water from the tank to flow into the pump chamber.

In order to regulate the height of washing 15 water in the tank 18 so as to keep the machine working at maximum efficiency, an overflow tube 88 is seated on and affixed rigidly to the valve plug 102 by a water-tight connection. This tube is spaced from the pump tube 80 and is 20 preferably flush with the inner surface of the plug 102. When the plug 102 is rotated so that its outlets 104 do not coact with outlets 101, water must pass over the top of tube 88 and pass 25 downwardly between it and the pump tube 80 into the pump chamber 25 in order to leave the tank.

An overflow shield 89 may be fitted over and spaced from the overflow tube 88 to prevent 30 swirling of water at the top of the overflow tube. 35 This shield is supported by posts 94 on the pump cover by crimping inwardly the lower rim of the shield as at 93 so it may be snapped into place in grooves 95 provided for that purpose in posts 94. These posts also act as vertical 40 baffles to retard rotary movement of the water adjacent the central portion of the chamber. The apron 90 which is clamped about the shield 89 (Figs. 1, 3 and 4) acts to prevent food particles which settle down into the well chamber 45 40 from returning to the main body of washing water. Baffles 92 are placed on the pump cover 24 to further retard swirling of the water in the well chamber.

An impeller guard 117 is placed over the impeller 83 to prevent dishes or silverware from falling onto the impeller. This guard may be integral with the dish racks 116. In machines of the impeller type, it has been found desirable to provide baffles on the tank bottom to slow down 50 the rapidly swirling water and to feed it onto the impeller blades. In the present invention baffles 118 (Fig. 12), affixed to the impeller guard 117, are utilized for this purpose. I have found that an efficient action is obtained by curving 55 these baffles convexly to the direction of rotation of the impeller. In addition to feeding the impeller, this baffle structure greatly reduces turbulence adjacent the bottom of the tank, so 60 the food particles forced outwardly by centrifugal motion of the water settle to the bottom of the tank, descend along the inclined bottoms 20 and 21 thereof and pass into the well chamber 22.

The dish holding rack 116 may be of any suitable construction such as that disclosed in co-pending application, Serial No. 433,206, filed March 5, 1930, by Edgar S. Stoddard. Adjacent the outer portion of this rack is mounted the silverware rack 120 (Figs. 9, 10). The body portion of this silverware rack is curved to correspond to the curvature of the tank wall and is provided with a number of vertical silverware receiving compartments 121, which extend 70 downwardly substantially one-half the distance 75

to the bottom of the rack. Adjacent the lower portion of these compartments the rack is provided with a centrally positioned and longitudinally extending bar 122, the upper portion of which extends through the walls of the compartments to form a central partition. The bottom 123 of the silverware rack preferably declines from its central portion outwardly to insure adequate draining of wash liquid and food particles. The rack is open at its sides between the bottom 123 and the lower portion of the compartments in order that wash liquid may be projected directly against the lower portion of silverware therein, and directly and by deflection against the upper portion of said silverware. Baffle strips 125 extend longitudinally of the rack substantially midway between the bottom 123 and the lower portion of the compartments, and act to prevent silverware from sliding out of the rack and possibly into the impeller.

An important feature of this silverware rack is the material from which it is made. It has been found that metal racks scratch and nick the silverware even when it is carefully placed within the apertures 121. The silverware is also rattled about by the spraying action of the washing liquid causing it to become marred. For these reasons it has been found necessary to make the basket from materials of a lesser degree of hardness than that of the silverware. "Bakelite" has been found to be very satisfactory for this purpose.

Inlet conduit 50 (Figs. 1, 7) is made up of a plurality of cooperating tubes. An inlet funnel 52 is threaded at 53 for the reception of a funnel tube 54. This funnel tube is adjustably mounted for rotation and longitudinal movement within a horizontal inlet tube 55. Upon the inner end of the funnel tube 54 are a plurality of raised stop and spacing members 56 which coact with a stuffing nut 57 to provide a substantially water-tight joint and to prevent outward movement of the funnel tube therebeyond. The upper portion 68 of the double elbow 57 receives the horizontal inlet tube 55. Threaded to the lower and outer portions of double elbow 57 is the vertical sliding inlet tube 58. This tube 58 is telescopically and rotatably mounted within the lower vertical inlet tube 59, and is provided at its lower end with stop and spacing members 56 which coact with a stuffing nut 60 to prevent upward movement of sliding tube 58 therebeyond.

In operation, the machine is moved to the vicinity of the sink and the inlet conduit system is adjusted in length and height so that the funnel 52 is positioned just beneath the faucet. The collar 61 is provided with a set screw or other conventional means whereby it may be seated against the stuffing nut 60 and secured in position to maintain the conduit system at the proper elevation with respect to the faucet and sink.

An inlet T 62 communicates with the lower end of vertical tube 59 through an upper arm 63. The inlet conduit is turned within the T and follows the T leg 65 to an aperture in the tank wall. A flanged inlet bushing 67 is screwed from the interior of the tank into the T leg 65, thereby forming a water-tight connection with the tank wall by means of suitable gaskets or washers.

The outlet conduit 130 leads from the pump chamber 25 upwardly and has a portion which is concentric but out of communication with the

inlet conduit 58, terminating in the horizontal outlet tube 131. The lower horizontal outlet tubes 132 extend from the pump chamber 25 and are provided with an emergency drain plug 133. An elbow 134 turns the outlet conduit upwardly and receives the lower vertical drain tube 135 in its upper arm. The upward end of vertical outlet tube 135 is flanged outwardly at 136 and held thereby within an interiorly threaded stuffing nut 137. This nut 137 is screwed upon the lower arm 138 of the T 62 holding the outlet system affixed to the inlet system.

An upper vertical outlet tube 139 communicates with an inner opening 140 in the double elbow 57, and extends downwardly through and concentric with inlet tubes 58 and 59. The lower portion of this vertical outlet tube is slidably received by the lower leg 138 of the T 62, and extends through said leg into the lower outlet tube 135. The inlet conduit 50 and the outlet conduit 130 are thus in concentric vertical relation for a portion of their length. To the outer end of the opening 140 in elbow 57 is affixed the horizontal outlet tube 131 which has a downwardly turned end portion to permit water from the tank to be discharged into a sink or other receptacle.

A flange 150 (Fig. 1) extends downwardly from the switch box 14 on the frame band 11 and has a horizontal loop 151 (Fig. 7) formed in its end portion. This loop 151 fits about the tube 59, thereby supporting the inlet and outlet conduit system upon the frame 10.

It is obvious that wash water admitted to funnel 52 passes by gravity through horizontal tubes 54 and 55, elbow 57, vertical tubes 58 and 59, and into the tank by way of leg 65 of the T 62.

Excess water in the tank passes over the overflow tube 88 and into the pump chamber. It is then ejected through horizontal outlet tubes 132, 134, lower vertical tube 135, upper vertical outlet tube 139, channel 140 of elbow 57, and horizontal outlet tube 131. The pump blades in the pump chamber rotate as long as the motor is in operation, thereby insuring that water in the pump chamber is adequately discharged.

To drain the tank after a washing or rinsing operation, the valve 102 is opened allowing all the water in the tank to be drained into the pump chamber from which it is discharged as described heretofore.

Referring to Figs. 1, 2, 5 and 6, the cover 28 is formed with the depending flange 46 (which is received within the upper portion of the tank); and an outwardly extending flange 47 which overlies the rim or lip 19 of the tank 18. About the wall of tank 18 at its upper end is an indented rib 21 which extends inwardly beyond the flange 46 forming a sheltering baffle for the joint between the flange 46 and the tank wall. The flange 46 is spaced inwardly from the tank wall forming a pocket 48 therebetween which prevents leakage of water, and yet permits sudden gusts of steam to raise the unsecured cover and to escape from the tank. With this form of cover structure no clamps are needed.

At times steam collects under the central portion of the cover 28, and to relieve any excess pressure at this point, I insert a ventilator 41 in the cover. As shown in Fig. 1, the ventilator 41 is inserted through an opening 40 in a depressed portion 39 of the cover 28, so that no part of the ventilator will project above the surface of the cover. This will permit a tray or other object to be placed upon the cover when closed.

The ventilator 41 comprises a hollow cylindrical rubber member open at the upper end and closed at its bottom 42. Adjacent its bottom 42 the ventilator is provided with openings 43 which communicate with a central discharge opening 44. Water sprayed from the impeller cannot pass out of the tank through this opening and yet any pressure due to steam may be relieved. The ventilator is held in place by a channel 45 which passes circumferentially thereabout adjacent its top. This channel receives the perimeter of the opening 40 and forms a substantially water-tight connection therewith.

In accordance with my invention, the cover 28 is supported from the band 11 of frame 10. An upper hinge portion 29 affixed to the cover 28 is joined by a rod 31 to a lower hinge portion 30 which is affixed to band 11. Frame leg 12 is slightly cut away at its upper end 32 to receive this lower hinge 30.

The lower hinge portion has an outer flat strip and an inner arcuate strip 38 which is shaped to fit band 11 and secured thereto by bolts 39.

The cover is supported in a horizontal position when open by means of a support rod 33 which is hinged at its lower end to one of the legs 12 of the frame 10 at 34. This rod 33 is Y-shaped at its upper end and has a cross piece and cover rest 35 connecting the arms of the Y. Pivotedly mounted on the cross piece 35 are the rods 36 which extend over to the upper hinge portion 29 and are pivotedly mounted thereto at 37. When the cover is closed, the support rod is in the position shown in Figs. 5 and 6. As the cover is opened, the support rod rotates outwardly about its pivotal connection 34, and when the cover has been opened to an inverted horizontal position the support rod is in such position that the cross piece 35 forms a stable rest for the cover. Dishes may then be placed on the inverted cover without danger of distorting the cover hinge.

Over the tank rim or lip 19 is placed a rubber cushion 49 (Figs. 1 and 5) upon which the flange 41 of the cover may rest. This cushion prevents chipping of dishes and glassware passed carelessly over the tank rim and substantially reduces any rattling of the loosely held cover. The cushion does not act as a gasket to prevent leakage of water because of its loose fit with the unclamped cover.

The cushion 49 is a continuous strip of rubber which in cross-section resembles substantially a numeral 9. It has an outwardly and downwardly curved outer lip portion which follows the curvature of the rim 19 and rests against the band 11. The downwardly extending inner or stem portion lies along the interior of the rim of the tank and against the tank wall. In this form of cushion the strain is placed upon the external lip portion holding the cushion on the rim 19 and thereby preventing the lower stem portion from buckling away from the tank wall. By giving the stem portion a snug fit with the tank wall, food particles cannot collect between the cushion and the tank wall.

In operation of the dishwashing machine faucet water is allowed to run into the inlet conduit 70 while the motor is running until it is seen to be discharged into the sink through the outlet conduit, whereupon it is then insured that the tank is filled with the proper amount of water. This amount may be of the order of five quarts, for example. The water is then shut off and the

partly submerged impeller is operated until dishes in racks held thereabove are sufficiently cleansed. The machine is then drained by operation of the push-pull wire connected to the drain valve. Ordinarily, the dishes will then be rinsed in a similar manner.

It will be seen that many variations are possible in the above described structure, and such modifications as are within the spirit of my invention are intended to be included in the appended claims.

I claim:

1. In a dishwashing machine, a tank, an inlet conduit communicating with the side of the tank, an outlet conduit communicating with the lower portion of the tank, a T having its horizontal arm connected to said inlet conduit and its lower arm communicating with the outlet conduit, a lower vertical inlet conduit communicating with the upper arm of said T, a vertical drain tube slidably and rotatably mounted in the lower arm of said T, said drain tube extending upwardly concentric to said inlet conduit, a vertical sliding inlet conduit mounted in said lower vertical inlet tube conduit, a double elbow connected to the upper ends of said slideable inlet conduit and said slideable drain tube, said elbow having horizontal ports for each of said slideable tubes, and separate horizontal conduits communicating with each of said ports. 30

2. In a dishwashing machine, a tank having an inlet opening and an outlet opening in the lower portion thereof, an inlet conduit communicating with said inlet opening, an outlet conduit communicating with said outlet opening, 35 said conduits having concentric vertical portions and horizontal terminating portions rotatably mounted with respect to said concentric portions.

3. In a dishwashing machine, a tank, an inlet conduit and an outlet conduit communicating with said tank, said conduits having vertical concentric portions, and terminating portions slidably mounted with respect to said concentric portions. 45

4. In a dishwashing machine, a tank, an inlet conduit and an outlet conduit communicating therewith, said conduits having lower vertical concentric portions, and upper vertical concentric portions slidably mounted for rotation and vertical adjustment, a double elbow connected to upper ends of said upper concentric portions, said elbow having horizontal non-concentric ports, and horizontal terminating tubes communicating with said ports, whereby adjustment 55 of one of said tubes effects adjustment of the other.

5. In a dishwashing machine, a tank, an inlet conduit and an outlet conduit communicating with said tank, said conduits having vertical concentric portions telescopically arranged for rotation and vertical adjustment of the upper portions thereof, means for maintaining said upper portions in fixed vertical adjustment, and horizontal terminating portions communicating with said upper portions, at least one of said terminating portions being telescopically arranged for horizontal adjustment. 65

6. In a dishwashing machine, a tank provided with a liquid chamber having a drain valve in the lower portion thereof, an actuating mechanism for said drain valve comprising a removable bushing extending through an opening in the wall of said liquid chamber below the nor- 75

mal liquid level therein, and in water-tight connection therewith, a housing extending through an opening in said bushing and rigidly attached in a water-tight connection to said bushing at that point, said housing exteriorly to said liquid chamber extending upwardly along the side of said tank and terminating in a slide tube, a valve handle slidably mounted within said slide tube

and held against rotation therein, and a drain valve wire affixed at one end to said valve handle and extending through said housing in slideable relationship therewith, said drain valve wire at its other end within said liquid chamber being affixed to said drain valve for operatively opening and closing the same.

EDGAR S. STODDARD.
